LAND SURFACING DEVICE

George B. Nelson, Redfield, Iowa

Application February 27, 1930. Serial No. 431,677

5 Claims. (Cl. 55—21)

The present invention relates to land surfacing devices and more in particular to farm implements or the like for conditioning and working farm land.

5 Among the objects of the present invention is to provide a novel mechanism or device having a plurality of individual land surfacing means in which certain of said means when manipulated, are adapted to swing either inwardly or 10 outwardly to provide a device of greater or less width, as desired.

The invention comprehends the idea of providing a land surfacing device having auxiliary land surfacing means normally adapted to be 15 connected to a main land surfacing means, and laterally thereof, but which means may be swung into a trailing position to the rear of said main surfacing means when, for any reason, it may be desired to provide a device of less width. Nor- 20 mally, and when the device is in operation for surfacing land or the like, the auxiliary surfacing means is connected with and laterally of the main surfacing means.

The main surfacing means is of a width which 25 will permit the same to pass, with sufficient clearance through an ordinary farm gate or the like, or to permit the movement of the same along a highway, or road, without obstructing or inter- 30 fering with the passage of vehicles thereby. In operation of the same, however, the auxiliary sur- 35 facing means are normally extending laterally of the main surfacing means for conditioning a larger area than would be possible were the same operated with the main surfacing means only. 40 Novel means are provided for operatively connect- 45 ing the auxiliary surfacing means to the main surfacing means for normally operating the device, this means, however, permitting the auxiliary surfacing means to swing into a trailing po- 50 sition behind the main surfacing means, the width of the same not being greater than the width of the main surfacing means. The device may then pass through an ordinary farm gate or may be pulled along a highway or roadway without 55 obstructing passage of vehicles thereby.

Another object of the invention is to provide a novel device, in which the hitch or connecting means between the auxiliary and main surfacing means may be readily manipulated to permit the 50 auxiliary surfacing means to swing into a trailing position with the main surfacing means when it is desired to pass through a gate or along a highway.

The invention further comprehends the idea 55 of providing a novel hitch or connecting means

which will not only permit of the above opera- 60 tion, but which is likewise adapted, upon move- ment of the main surfacing means, and with a minimum of turning of the auxiliary surfacing means, to again connect the same in normal op- 65 erative position and laterally of the main sur- facing means, after the device has passed through a gate or the like, or along a highway or roadway.

Another object of the invention is to provide a novel construction in a surfacing means, such 65 as a land rolling device, in which the tongue thereof may be used as a drawing means when the device is either horse or tractor drawn. When the device is drawn by tractor, the tongue there- 70 should be sufficiently low to provide a suitable 75 hitch with the tractor, yet for the same to be adapted for a team of horses, it is necessary that this tongue be higher. Means are therefore pro- 80 vided whereby this tongue may have the nec- essary adjustability and which may be raised or 85 lowered for positioning the same at any desired height for either of these purposes.

Means are further provided at or adjacent the 80 forward end of the tongue whereby a harrow or any other suitable device may be connected there- 85 to and be moved with the surfacing means and forwardly thereof, when the device is tractor drawn.

A still further object of the invention is to 85 provide a novel surfacing device, as for example, 90 a land rolling device, having a frame with rolling elements mounted therein, in which the means for drawing the device are connected to the frame thereof in substantially a horizontal plane pass- 95 ing through the center line of the rolling ele- 95 ments. By providing a connection which is substantially in a horizontal plane passing through the center of the rolling elements, there is no tendency of the rolling elements to dig into the surface of the ground and to pull the tongue 100 or drawing means downwardly which would be objectionable were the device being drawn by horses.

The invention further comprehends the idea 100 of providing a novel tongue supporting means, 105 which means is suitably mounted in the framework of the main surfacing means and with which is associated means for raising and lowering the same together with the tongue, means being like- 110 wise provided whereby the pull on the tongue or a substantial part thereof is transmitted to the frame and at a point or points in a substantially horizontal plane passing through or slightly above the center line of the rolling elements of the device. Means are further provided at the 110

forward end of the tongue and are connected to the frame in substantially or slightly above the horizontal plane passing through the center line of the rolling elements.

5 Other objects, features, capabilities and advantages are comprehended by the invention as will later appear and as are inherently possessed thereby.

Referring to the drawings:

10 Fig. 1 is a top plan view of an embodiment selected to illustrate the novel invention.

Fig. 2 is a vertical cross sectional view taken in a plane represented by line 2—2 of Fig. 8 of the drawings.

15 Fig. 3 is a vertical cross sectional view taken in a plane represented by line 3—3 of Fig. 1 of the drawings.

Fig. 4 is a fragmentary view in side elevation of the embodiment disclosed in Fig. 1 of the drawings.

20 Fig. 5 is a fragmentary vertical cross sectional view taken in a plane represented by line 5—5 in Fig. 1 of the drawings and disclosing in detail the construction of the tongue and supporting means therefor.

Fig. 6 is a fragmentary vertical view in elevation taken in a plane represented by line 6—6 of Fig. 1 of the drawings.

25 Figs. 7 to 10 inclusive are views illustrating the various positions of the auxiliary surfacing means, shown in the embodiment disclosed in Fig. 1 of the drawings, when the same are being placed laterally of or trailing the main surfacing means.

30 Referring now more in particular to the drawings, the embodiment selected to disclose the invention is shown as comprising a land rolling device having a main rolling means 1 to which are connected auxiliary rolling means 2 and 3 of similar construction, and which are adapted, when normally in their operative position as shown in Fig. 1, to move over an area of ground to be worked or conditioned laterally of that over which the main rolling means passes, but which may, by 35 manipulation of the means (to be hereinafter more fully disclosed) connecting the same with the main rolling means, be swung into a trailing position as shown in Fig. 8 of the drawings, for a purpose more clearly disclosed in the succeeding 40 paragraphs.

The main rolling means 1 comprises an elongated frame 4 having side pieces or members 5 and 6, and end pieces or members 7 and 8 of structural steel, wood or any other suitable material, connected together, as by means of bolts, rivets or the like to provide a rigid frame, to the end members 7 and 8 of which are mounted or connected bearings, such as 9, by means of bolts 10 or the like. In these bearings are mounted 45 the ends of a shaft 11 upon which are rotatably mounted a plurality of rolling elements 12, these elements being adapted to move over the surface of the ground upon movement of the device. A tongue 13 (to be hereinafter more fully disclosed) is suitably connected to the frame 4 for connecting the same to a tractor or to provide means whereby the device may be drawn by a team of horses.

The frame 4 of the main rolling means may 50 be of any desired length, but preferably about 12 to 14 feet, such that the same may, with sufficient clearance, pass through the ordinary farm gate. In order that the device may condition and prepare a greater area than could be worked by the 55 main rolling means, the auxiliary rolling means

2 and 3 are connected to and laterally of said main rolling means 4, novel means being provided for connecting the same thereto, whereby these auxiliary rolling means may swing inwardly so as to pass through a gate of sufficient width to allow passage of the main rolling means.

80 Each of these auxiliary rolling means or units are constructed similarly to the main rolling means or unit, the same having a frame 14 of any suitable material, this frame having side members 15 and 16, and end members 17 and 18 connected together by bolts, rivets or the like to provide a rigid construction. Similarly to the main frame, bearings, such as 19, are mounted or secured to the end members 17 and 18 in which are journaled the ends of a shaft 20 having rolling elements 21 rotatably mounted thereon. Each of these auxiliary rolling means or units is provided with a forwardly extending tongue or draw-bar 22, the same having an end bent to contact the angular frame 15 and being secured thereto by rivets 23 and 24 or the like. Diagonal braces 25 and 26 are further provided and are connected adjacent the forward end of the tongue 22 and to the frame 15 to reinforce and 90 strengthen the tongue connection with the frame.

95 The forward end of this bar or tongue is provided with a bolt hole or aperture 27 adapted to register with a similar hole 28 in a bar or link 29 and with another hole 30 of a bent plate 31 spaced from said bar or link and secured thereto by rivets 32 or the like. A pin 33, bolt or similar means is provided for pivotally connecting each of the tongues 22 to the bars or links 29.

105 A bar or link 29 is provided at each end of the frame of the main rolling means or unit and is adapted to extend laterally beyond the same and to provide a connecting means whereby there is a small amount of overlapping of the rolling means of the auxiliary units with that of the main unit. 115 Each of these bars 29 has an end pivoted to the side frame members 6 by means of a bolt 34 or the like, which bolt passes through a hole in a lug member 35 secured to the frame and a similar hole in the frame 6, a bolt hole in the member 120 29 registering with these holes and through which the bolt passes. The member 29 is held in the position as shown in Fig. 1 of the drawings by means of a diagonal link member or bar 36 pivoted to the end of the frame member 5, the 125 other end having a hole 37 therein aligned with a similar hole 38 in a crimped or bent member 39 adapted to register with a hole 40 in the bar 29 and through which passes a removable pin 41, or bolt or the like.

130 When it is desired to allow the auxiliary rolling means or units to swing into the position as shown in Fig. 8 to permit the passage of the device through a gate or to draw the same along a highway or roadway, the pin 41 at both sides of the 135 device is removed at which time the bars 29 will pivot rearwardly, upon a further movement of the main rolling unit, to the position shown in full lines in Fig. 7 of the drawings. Each of the bars 29 is further provided with another hole 42, 140 which hole, when the bar 29 is in the position shown in full lines in Fig. 7 of the drawings, is adapted to register with a hole 43 of the bar or tongue 22 and the hole 44 of a bent or crimped plate 45 secured by means of rivet 24 to the frame 145 15 of the auxiliary unit and tongue 22. The removable pin or bolt 41 may then be inserted through these aligned holes so that, upon further forward movement of the device, each of the auxiliary units 2 and 3 will swing inwardly to the 150

position shown in Fig. 8 of the drawings and to permit the device to pass through an ordinary gate or to pass along the highway without obstructing traffic passing thereby. Each of the 5 bars or links 36 may be swung inwardly out of the way and are engaged and held by the turned-up edge 46 of the lug angles 47 secured to the ends of the frame 4 of the main rolling means or unit, as clearly shown in detail in Figure 2 of the drawings.

After the device has passed through the gate, or when it is again desired to bring the auxiliary units from the trailing position as shown in Fig. 8 of the drawings, into the position shown in Fig. 15 of the drawings, the device is stopped, the pins 41 are removed from the aligned holes 44, 42 and 20 43, and the inside corners 48 of the auxiliary rolling means or units 2 and 3 are pulled rearwardly a slight amount to turn or move the same to the 25 position shown in dotted lines of Fig. 9 of the drawings and to swing the rear end of the bars 29 inwardly. The pins 41 are then inserted into the hole 42 so that the ends thereof will pass between the inner braces 26 of each of the sections and the tongue 22 thereof. The main rolling means or unit 1 is then backed or moved rearwardly until these auxiliary units are spaced apart about or substantially a distance equal to the width of the main rolling means or unit, as 30 shown in full lines in Fig. 9 of the drawings. The device is then stopped, the pins 41 removed from the holes 42, and a slight pull exerted against the outer corners 49 of the auxiliary units 2 and 3 to turn the same inwardly a small amount 35 and to swing the rear end of the bars 29 outwardly past the center and longitudinal axis of the tongue or draw bar 22, as shown in full lines in Fig. 10 of the drawings. Upon a rearward movement of the device, the auxiliary units 2 and 3 and the bar 29 will assume intermediate positions as shown in dotted lines in Fig. 10 of the drawings.

The links or bars 36 are removed from their respective bracket or lug 47 to a position as shown 45 in dotted lines in Fig. 10 of the drawings, in which position the holes 37 and 38 therein will register with hole 40 of each of the bars 29 upon a further rearward movement of the main rolling unit 1. When these holes have registered, the 50 pin 41 is inserted therethrough to lock or hitch the auxiliary rolling units to the main rolling units in the position shown in Fig. 1 of the drawings and laterally thereof. When the device is in the position as shown in this figure of the drawings, the same is in its normal operative position 55 and may be used for further conditioning or preparation of the farm lands.

The tongue 13, providing means for drawing the main and auxiliary rolling units, is shown as 60 being formed of an elongated member 50 preferably of wood, although any other material may be used in the construction thereof. This member 50 is reinforced by means of a plate 51 having a top part 52 and a bottom part 53 extending along the tongue 13 and being secured thereto by means of bolts, rivets or the like 54. This plate 51 is bent upon itself to provide an end part 54^a adapted to receive a ring or the like of a neck yoke, when the device is being drawn 65 by horses, this end being further bent upon itself to provide a downwardly extending part 56 which acts as a stop for the neck yoke. The end part 54^a is further provided with a hole or aperture 55 for receiving a cable, hook, or the like and 70 for securing the device to a tractor or other prime

mover. Hooks 57 and 58 are secured to the sides of the tongue 13 and hook 59 is secured to the bottom and at the forward ends thereof for purposes to be hereinafter disclosed.

The rear end of the tongue is further reinforced by a top plate 60 to which is secured a bent plate 61 by means of a rivet 62 or the like, between which and the tongue 13 is carried a cross-bar to which whiffletrees are secured, a bolt or the like passing through a hole therein adapted to register with holes 63 and 64 of the plate 61 and tongue 13, respectively. The rear end of this tongue 13 is carried or mounted by means of bolts 65 to a tongue support or carriage 66 mounted in the frame 4 of the main roller section or unit.

This support comprises spaced elongated side members 67 and 68 adapted to receive the tongue 13, the rear ends thereof being pivotally mounted by means of bolts 69 or the like, to the sides of an inverted U-shaped bracket or lug 70 suitably connected to the rear frame member 6, while the forward end of these side members are connected to lug angles 71 which are secured to the top surface of an angular bracket member 72. Secured to the forward frame member 5 is an inverted U-shaped bracket or lug 73 of similar construction to the bracket 70, the same having vertical sides adapted to guide the members 67 and 68 as these members are raised and lowered about their pivot points. Straps 74 and 75 having their ends secured to the frame members pass over the top of these U-shaped brackets 70 and 73, respectively, for reinforcing these brackets in a lateral direction, while a strap 76 connects these brackets 105 to reinforce the same in a forward and rearward direction.

This strap 76 is connected to the bracket 70 by means of a bolt 77 or the like, this bolt passing through aligned openings or holes therein and in 115 the strap 74 and the top part of the U-shaped bracket 70. The forward end of this strap 76 is provided with a hole or opening adapted to register with similar holes in the strap 75 and the top plate of the U-shaped bracket 73, through 120 which extends a bolt 78 or the like, having a lock nut 79, and the end of which threadedly engages a cross-head or block 80 mounted in the members 67 and 68. When it is desired to raise or lower the tongue 13, the bolt 78 may be turned 125 in the cross head 80 for movement of the tongue support about its pivot points in the U-shaped bracket 70. The adjustability of this tongue is very desirable in order that the device may either be drawn by horses or tractor, or the like. When 130 the tongue is in a lowered position, the same is adapted to be connected to a tractor or other prime mover, but when it is desired to draw the device with horses, it is necessary that this tongue 13 be raised from its former position.

Diagonal links or bars 81 and 82 are pivotally connected to the downwardly extending legs 83 of the bracket 72 and are likewise pivotally connected between the lug angles 84 and 85 secured adjacent the ends of the frame member 5, these 140 bars or links being adapted to transmit a large part of the force applied to the tongue 13 to the outer ends of the frame of the main roller unit.

Tension cables 86 or the like are connected to each of the hooks 57 and 58 and are connected to and adjacent the ends of the frame member 5 and forwardly of the bearings 9 of the main rolling means. Turn buckles 87 are provided for taking up any slack in these cables 86. These cables are applied when the device is to 145

be drawn by a tractor in order to brace the tongue should one end of the roller strike an obstruction, but they are omitted when horses are used.

5. It will be seen that the force or forces being applied to the tongue 13 and transmitted by way of the cables 86 and bars 81 and 82 is transferred and applied to the frame of the main rolling means or section at a point or points in 10 a plane substantially passing through the center line of the shaft 11, and rolling elements 12. This construction is of importance in a device of this character, inasmuch as there is substantially no moment or force being applied to the main 15 frame which would act through any great distance and which would have a tendency to cause the rolling elements thereof to dig into the ground. Any digging of the rolling elements into the ground is substantially eliminated and 20 there is, therefore, no downward movement of the tongue, which movement is objectionable when the device is being horse drawn.

When the device is to be drawn by tractor, a harrow or any other similar device, may be 25 connected to the hook 59 at the forward end of the tongue 13 and forwardly of the main rolling means or section.

While I herein describe and upon the drawings 30 show an illustrative embodiment of the invention, it is to be understood that the invention is not limited thereto, but may comprehend other constructions, arrangements of parts, details and features without departing from the spirit of the invention.

35. Having thus disclosed the invention, I claim:

1. In a land surfacing device having a frame and surfacing means mounted therein, a tongue support pivotally mounted in said frame, laterally extending brace members extending therefrom and connected to said frame, a tongue 40 mounted in said support, flexible adjustable means connected to the forward end of said tongue and to said frame, and means for raising and lowering said tongue and support.

45.

50.

55.

60.

65.

70.

75.

2. In a land surfacing device, a main surfacing means mounted in a frame, an arm member pivoted to said frame and adapted to project laterally therefrom, another arm member pivotally connected to said frame, means for connecting the ends of said members together to hold said first member in said laterally projected position, an auxiliary surfacing means connected intermediate the ends of said first member and laterally of said main surfacing means, and means for connecting the end of said first member to said auxiliary surfacing means when said member is in a trailing position. 80

3. In a land surfacing device, a main surfacing means mounted in a frame, an arm pivotally connected to said frame and adapted to extend laterally therefrom, an auxiliary surfacing means connected intermediate the ends of said arm, and means for connecting the outer end of said arm to said auxiliary surfacing means when said arm is in a trailing position. 85

4. In a land surfacing device, a main surfacing means mounted in a frame, an arm pivotally connected to said frame and adapted to extend laterally therefrom, an auxiliary surfacing means 90 connected to said arm, and means for locking said arm and auxiliary surfacing means together whereby the same move together when said arm is in a trailing position.

5. In a land surfacing device, a main surfacing means mounted in a frame, an arm pivoted to said frame and adapted to project laterally therefrom, an auxiliary surfacing means having a 100 forwardly extending draft member connected intermediate the ends of said arm, said arm having an opening at the outer end thereof adapted to register when in a trailing position with openings on said draft member, and means engaging in said aligned openings for locking said auxiliary surfacing means and arm together. 105
